UNITED STATES PATENT OFFICE.

JOHN CLULEE, OF WALLINGFORD, CONNECTICUT, ASSIGNOR TO THE INTERNATIONAL SILVER COMPANY, OF MERIDEN, CONNECTICUT.

DESIGN FOR A HANDLE FOR SPOONS, FORKS, OR SIMILAR ARTICLES.

SPECIFICATION forming part of Design No. 32,562, dated April 24, 1900.

Application filed March 28, 1900. Serial No. 10,556. Term of patent 7 years.

To all whom it may concern:

Be it known that I, JOHN CLULEE, of Wallingford, in the county of New Haven and State of Connecticut, have invented and produced a new Design for a Handle for Spoons, Forks, or Similar Articles; and I do hereby declare the following, when taken in connection with the accompanying drawing and the letters of reference marked thereon, to be a full, clear, and exact description of the same, and which said drawing constitutes part of this specification, and represents a face view of a handle embodying my design.

This invention relates to a design for a handle for spoons, forks, and similar articles; and the design consists in the configuration and ornamentation, as hereinafter described, and shown in the accompanying drawings.

In outline the handle follows the general fiddle-back pattern, and its edge is bordered

by a narrow interrupted beading, consisting of short plain sections A and beaded sections B. On opposite sides of the outer end are scrolls C, connected by a scroll-like tip D and united by a shell-like scroll E, which forms 25 the end of a plain panel F, which tapers downward and extends throughout the length of the handle, all as shown in the accompanying illustration.

I claim—

The design for a handle for spoons, forks and similar articles, as herein shown and described.

In testimony whereof I have signed this specification in the presence of two subscribing witnesses.

JOHN CLULEE.
